(57) **CLAIM**

The ornamental design for a mud ring, as shown and described.

DESCRIPTION

FIG. 1 is a perspective view of a first embodiment of a mud ring for an electrical box according to the present invention; FIG. 2 is a left side view of the mud ring according to the first embodiment;

FIG. 3 is a front plan view of the mud ring according to the first embodiment;

FIG. 4 is a right side view of the mud ring of the first embodiment;

FIGS. 5 and 6 are top and bottom view respectively of the mud ring according to the first embodiment;

FIG. 7 is as rear view of the mud ring according to the first embodiment.

FIG. 8 is a perspective view of the mud ring according a second embodiment having a second pair of screw holes formed therein;

FIG. 9 is a left side view of the mud ring according to the second embodiment;

FIG. 10 is a front plan view of the mud ring according to the second embodiment;

FIG. 11 is a right side view of the mud ring according to the second embodiment;

FIGS. 12 and 13 are top and bottom views, respectively, of the mud ring according to the second embodiment; and,

FIG. 14 is a rear view of the mud ring according to the second embodiment.
